CLAIM

I claim the ornamental design for a folder, as shown and described.

DESCRIPTION

FIG. 1 is a front, right, top perspective view of a folder for which a front, left, top perspective view is a mirror image thereof;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken line in FIG. 1 is included for the purpose of showing a feature of the folder that forms no part of the claimed design.
